MOP

Filed Sept. 15, 1927

Charles V. Anderson
Inventor

By
Charles V. Anderson
Attorney:

UNITED STATES PATENT OFFICE.

CHARLES V. ANDERSON, OF CINCINNATI, OHIO.

MOP.

Application filed September 15, 1927. Serial No. 219,726.

This invention relates to mops and particularly mops generally utilized for cleaning and polishing floors and other wooden surfaces having a high polish or finish 5 thereon.

One object of the invention is to provide a mop of exceedingly simple construction, capable of being produced at a comparatively low cost.

10 Another object is to provide a strand-carrying frame of light weight material, a novel arrangement being provided for reinforcing said frame so as to prevent flexing of said frame.

15 The mop, in its preferred form, is reversible and a still further object is to provide a simple arrangement for limiting the turning movement of the handle with respect to the strand carrying head when the 20 mop is being reversed.

With these and other objects in view the invention consists in certain details of construction and combinations and arrangements of parts, all as will hereinafter be 25 more fully described and the novel features thereof particularly pointed out in the appended claims.

In the accompanying drawings,

Figure 1 is a plan view of a mop embodying the present improvements;

Fig. 2 is a perspective view of a mop head detached from the handle and opened;

Fig. 3 is an elevation of the interior of the mop head illustrating the connections for 35 securing the two ends of the head together when the latter is mounted on the handle;

Fig. 4 is a plan view showing the strand supporting frame mounted on the handle socket;

40 Fig. 5 is a view on the line 5—5 of Fig. 4; and

Fig. 6 is a similar view showing the position of the handle and head when the mop is reversed.

45 The handle 10 may be secured in any desired way to a suitable member such as socket 11, which with the exception of one or two features to be later described may take any desired form or shape. Preferably, one

50 end of socket 11 is formed with bifurcation 12 between which one arm 13 of an angularly shaped connector is pivotally secured as by an ordinary bolt 15. Between arm 13 and one bifurcation, a friction element, such 55 as a rubber washer 14 is secured on the bolt 15. When the nut on bolt 15 is tightened,

the friction of said washer aids in preventing turning of the socket and connector.

The other arm 13^a of the connector has permanently attached thereto one end of a 60 strand carrying frame 16 which is made up of thin, flat spring metal whose free end is adapted to be slipped through a casing or pocket 17 formed in or on the material carrying the mop strands 18. In assembling 65 the mop this free end of frame 16 is placed on a threaded pin 19 mounted on arm 13^a of said connector, this end of the frame being provided with a series of holes 20 for the reception of pin 19. The provision of this 70 series of holes 20 makes it possible to alter the diameter of frame 16 to compensate for shrinkage of casing 17. To retain the free end of the frame on pin 19, a thumb nut 21 for said pin is provided and to prevent flexing of said frame, laterally, of the strip of which it is formed, one edge of arm 13^a of the connector is offset or formed with a flange, as at 13^b, against which the edge of the frame engages when secured to arm 13^a. 75

As illustrated, the strands 18 project from both sides of casing 17, the mop being adapted to be reversed, whereby the strands at either side of the casing may be utilized. This, of course, requires that the angular 80 position of the handle 10 with respect to frame 16 be capable of being altered so as to extend upwardly, for instance, from the frame when the latter is flat on the floor. The pivoted connection between the socket 90 11 and arm 13 of the connector to which the frame is attached, permits of this adjustment but to limit the relative turning movements of the socket and connector, one bifurcation of the socket and the arm 13 are 95 provided with cooperating stop elements. Preferably, these elements consist of a protuberance 22, formed by an indentation in the bifurcation, which is adapted to engage the edge of arm 13 a portion of said edge being 100 cut away as at 23 whereby the handle will be free to turn the desired distance, in one direction, before the projection 22 comes in contact with said edge.

To add to the appearance of the mop when 105 assembled, the ends of casing 17 are adapted to be secured together by fastening elements such as the ordinary hook and eye 24.

A mop embodying the present improvements is comparatively inexpensive due to 110 the simplicity of its several parts. It is also convenient to use on account of being ex-

tremely light, the metal constituting the strand-carrying frame adding little weight to the mop. Further, the stop elements for limiting relative movements of the handle and frame cannot become detached or lost as they are formed integrally with major parts of the device.

What I claim is:

1. A mop comprising a handle, a frame attached to said handle and on which the mop strands are removably carried, said frame being formed of flat spring material, and means carried by said handle having a flat face against which said frame engages and also provided with a projection engaging an edge of said frame for preventing lateral flexing of the frame.

2. A mop comprising a handle, a connector attached to said handle, a pliant casing carrying a multiplicity of mop strands, a stiffening member having one end permanently attached to said connector, the other end of said member being adapted to be projected through said casing while the member is attached to said connector, and means for detachably securing said other end to said connector.

3. A mop comprising a handle, a connector attached to said handle, a pliant casing carrying a multiplicity of mop strands, a stiffening member having one end permanently attached to said connector, the other end of said member being adapted to be projected through said casing, means having a flat face against which said member engages and provided with a projection adapted to engage an edge of said stiffening member for preventing flexing of said stiffening member, and means for detachably securing said other end of said member to the connector.

4. In a mop, a handle, a pliant casing having a plurality of strands thereon, a con-

nector carried by said handle, said connector having a lateral projection having an overhanging flange at one edge thereof, a stiffening member adapted to extend through said casing, and means for attaching said member to said connector with one edge of said member engaging against the flange on said connector.

5. In a mop, a handle, a pliant casing having a plurality of strands thereon, a connector carried by said handle, said connector having a lateral projection with an overhanging flange at one edge thereof, a stiffening member adapted to extend through said casing one end of said member being permanently attached to said connector, and means for detachably securing the other end of said member to said connector with one of its edges engaging the overhanging flange of said connector.

6. A mop embodying a handle, a frame formed of flat spring material upon which mop strands are removably mounted, and means located at one end of said frame for attachment to the handle and for attaching the other end of said frame.

7. A mop embodying a handle, a frame upon which mop strands are removably carried, said frame consisting of a pliant metal strip, a connector fixedly secured to one end only of said strip, means for securing the free end of the strip to the connector, and means for securing the connector to the handle.

8. In a mop, a pliant casing carrying mop strands, a frame consisting of a pliant metal strip, a connector permanently secured at one end of the strip, the opposite end being free for passage through the casing, means for securing the free end of the strip to the connector, a handle, and means for securing the connector to the handle.

CHARLES V. ANDERSON.
